TELEPHONE SYSTEM

Charles Edmund Beale, Chidwall, Liverpool, Idris Trevor Richards, Wavertree, Liverpool, and Owen Avis Pearce, Barnston, England, assignors to Associated Telephone & Telegraph Company, Chicago, Ill., a corporation of Delaware

Application September 17, 1938, Serial No. 230,416
In Great Britain October 6, 1937

20 Claims. (Cl. 179—26)

The present invention relates to telephone systems and is more particularly concerned with the provision of telephone service in an area involving a main exchange, a few satellite exchanges, and a number of small exchanges provided with automatic switching equipment controlled from the main exchange which will be referred to hereafter as R. C. X.'s. The invention is mainly concerned with the equipment in the satellite exchanges and particularly with switches usually known as discriminating selector repeaters which enable economy to be achieved in the use of junctions and switching equipment for giving the facilities required. The chief object of the invention is to provide improved types of discriminating selector repeater which offer special advantages in systems operating on the general principles referred to above.

According to one feature of the invention in a discriminating selector repeater unit including a hunting switch adapted to select an idle line extending to a main exchange and a numerical switch adapted to extend connections to local switches or adjacent exchanges, impulses transmitted over the junction from the main exchange are adapted to effect the setting of the numerical switch.

According to another feature of the invention in a discriminating selector repeater unit including a hunting switch adapted to select an idle line extending to a main exchange and a numerical switch adapted to extend connections to local switches or adjacent exchanges, impulses transmitted over the junction from the main exchange are adapted to be repeated over the wipers of the numerical switch.

A further feature of the invention is that in a discriminating selector repeater unit including a hunting switch adapted to select an idle line extending to a main exchange and a numerical switch adapted to extend connections to local switches or adjacent exchanges, impulses transmitted over the junction from the main exchange are adapted to be repeated over the leads over which the unit was seized.

According to still another feature of the invention in a discriminating selector repeater unit including a hunting switch adapted to select an idle line extending to a main exchange and a numerical switch adapted to extend connections to local switches or adjacent exchanges, the numerical switch is arranged to be capable of operation either by a calling subscriber or by an operator to whom connection has been extended in the main exchange.

The invention will be better understood from the following description of examples of its application to a system including a main exchange, a tandem satellite and a plurality of R. C. X.'s one of which is of the tandem type and gives access to what is described as a terminal R. C. X. Reference should be had to the accompanying drawings comprising Figs. 1-7 of which Fig. 1 represents diagrammatically the general trunking layout of the system, while Figs. 2-4 and 5-7 show respectively the circuits of two different varieties of discriminating selector repeater.

Considering first Fig. 1, the subscribers on the main exchange and the subscribers on the tandem satellite exchanges are provided with dial telephones and are permitted to set up automatically calls to other subscribers on their own exchange. For all external calls the subscribers are instructed to dial a distinctive digit which routes their connection to the manual board at the main exchange where their requirements are attended to by the operator who connects them automatically with the required subscriber on the external exchange.

The subscribers on the tandem R. C. X.'s and the terminal R. C. X.'s are not provided with dial telephones and for all calls they must call or ring down to the operator at the manual board in the main exchange who extends them automatically to subscribers in their own exchange or to subscribers in a different exchange as required. Generally speaking the main exchange may cater for say 1600-3000 lines, the tandem satellite for say 100-200 lines and the tandem R. C. X. for say 10-50 lines.

The terminal R. C. X. is shown in Fig. 1 as an all-relay board and is assumed to cater for 10 lines. As a special feature of this board since only one link circuit is provided it is arranged that the dialling and ringing equipment are located in a common group divorced from the link circuit. By this means when the link is in use on a local call it is still possible to complete an incoming trunk call over the free common equipment. The same facilities could of course be provided using 12-point uniselectors connected back to back in place of relays and in point of fact if there was ever any possibility of the terminal R. C. X. being converted to a tandem R. C. X. at some later date, it would be preferable to use uniselectors in place of relays since the former lend themselves more readily to discriminative selection.

It will be appreciated from the foregoing that in an area of the type described special problems

arise in connection with the design of the discriminating selector repeaters, hereafter termed D. S. R.'s, which are used in the tandem satellite exchange and as will appear from the following description particularly on certain types of call.

For instance in the case of local calls the D. S. R.'s will be required to function in the normal manner of performing a rotary hunting operation after the vertical motion and then repeating the digits forward to set up the local connection. On other types of call, for instance external calls, they will be required to drop back after the operator has been connected with and then respond to digits transmitted by the operator in order to set up the external connection. In other circumstances where the D. S. R. is terminating a junction from an adjacent tandem R. C. X. it will be necessary for the D. S. R. in the case of a call originated at the tandem R. C. X. or a more distant terminal R. C. X. to signal forward to obtain connection with the operator and then if the calling subscriber requires connection to another subscriber on either the tandem or terminal exchange the D. S. R. must be adapted for dialling back over its own incoming circuit under control of the operator in order to repeat backwardly the pulses necessary for setting up the local connection.

The operation of the system for the above kinds of calls as well as others will be better appreciated from the following description of the sequence of operations which take place, reference being had to the trunking diagram Fig. 1.

When a subscriber S1 on the tandem R. C. X., 25 TR calls, it will be understood that a free both-way junction equipment BE is selected over a relay chain allotter arrangement whereupon a link circuit L, preselected over an allotter LA, causes a line finder LF to hunt for the calling line. At 30 the same time the calling signal is repeated in the form of a pulse of ringing current over the junction and bothway junction equipment BE1 to the incoming D. S. R. D1 at the tandem satellite exchange and in response to the signal this 35 switch associates itself with a free bothway junction to the main exchange M over its associated junction hunter switch JH3 and the bothway junction equipment BE3. The signal is thereupon repeated to the manual board terminating 40 the junction so as to bring the operator into the connection and she ascertains the required number from the calling subscriber on the tandem R. C. X. In order to verify the correctness of the 45 number which he gives as his own she then dials back through the incoming D. S. R. switch D1. Generally speaking, verification is required on all 50 calls from R. C. X.'s since otherwise the operator will have to meter solely against information received from the calling party which may or may 55 not be correct.

Reverting now to the operation of the incoming D. S. R. during verification, the operator first of all dials the digit designating the incoming connection so that the wipers are raised to the appropriate level in the usual manner. The switch does not hunt however and in place of this a relay is operated over the vertical bank and wiper and serves to by-pass the bridge circuit in the D. S. R. and enable further digits to be repeated 60 back over the incoming junction to set up the verification connection in the R. C. X. When this is done the operator should encounter a busy signal whereupon she cuts in and asks the subscriber to repeat his number as a check against 65 the original information.

The setting up of the verification connection at the R. C. X. will have necessitated the operation of the connector half FS of the link L already seized by the subscriber on the origination of the call, and if it is now desired to extend him to a local subscriber on the same exchange the operator must first of all release the connector half of the link and then reset it by dialling on to the subscriber required. This is achieved by extending a high voltage pulse from the manual board 70 via the D. S. R. in the tandem satellite which is received at the R. C. X. on a gas discharge tube and relay in series.

In case there are two R. C. X.'s connected in series to the tandem satellite as shown in Fig. 1, 15 it will be necessary to arrange for the tandem R. C. X. to relay the high voltage pulse to the terminal R. C. X., R in the case of a call originated from the latter exchange. Incidentally the wipers of the incoming D. S. R. at the tandem 20 satellite are also reset to normal as a result of this releasing pulse.

If the call is to be completed to a subscriber on the same exchange as the calling party, the operator again dials into the incoming D. S. R., 25 which raises its wipers to the same level as before and operates the relay which completes the bypass dialling circuit to the incoming junction. The operator continues to dial back over the junction to set the connecting link already in use 30 to connect with the wanted subscriber who is thereupon rung. When he answers and the subscribers commence to converse, the operator withdraws from the connection thereby releasing the incoming D. S. R., in the tandem satellite 35 and also the link circuit in any tandem R. C. X., which may have been passed through on the way.

In case the call is intended for a subscriber on the tandem satellite, the operations are the same up to the extension of the high voltage pulse to clear down the verification circuit. The operator now dials the local number of the tandem satellite, whereupon the incoming D. S. R., raises its wipers to a position in which a relay is operated 40 to initiate the hunting operation. The wipers thereupon cut in and select the local train of switches which in Fig. 1 might be connected to any of the levels 1-5 and the connection is completed in the usual manner. When this is done 45 and the subscribers are in conversation, the operator withdraws from the connection and the R. C. X., and the tandem satellite are left connected together.

In case the call is intended for a subscriber on another R. C. X. adjacent to the tandem satellite, the operation is the same as described up to the release of the verification connection. The operator then resets the incoming D. S. R. to a level such as 6 upon which the hunting operation is initiated to select a junction to the adjacent R. C. X. Further digits are then dialled to connect with the required subscriber on the adjacent R. C. X. and when the two subscribers are in conversation, the operator clears her connections and the two R. C. X.'s are left connected together via the tandem satellite exchange while the junction from the latter to the main exchange is released.

In case the call is intended for a subscriber on the main exchange or a subscriber on a satellite accessible thereover, the operation is the same as described up to the release of the verification connection. The operator then takes up the other plug of the cord circuit in use and plugs it into 70 75

a jack extending to the local switches (not shown) or into a jack connecting with the required adjacent exchange over the junctions such as J_1 and J_2 . Further digits are then dialled 5 to connect with the required subscriber and when the subscribers are in conversation the operator clears out of the connection. All apparatus and junctions taken into use are then retained until the subscribers hang up whereupon the operator 10 is signalled accordingly and withdraws her plugs to bring about release.

In case a call is originated by an automatic subscriber S_2 on the tandem satellite exchange he is connected via a line finder SF_1 to a local 15 D. S. R., LD which differs from the incoming D. S. R.'s such as D_1 and D_2 in that it is not required to repeat dialled impulses backwardly over its own incoming circuit. If a local subscriber's number is dialled, the D. S. R. absorbs 20 the first digit and upon the reception of the second digit raises the wipers to the level accommodating the required group of final selectors over which it hunts to pick up a free final selector. The next two digits are repeated by the D. S. R. 25 to set the final selector wipers into engagement with the desired subscriber's line. Thus local calls proceed in a fully automatic manner and such calls are automatically metered.

If however the subscriber requires a call external to his own exchange he dials a distinctive digit such as 0 which raises the D. S. R. wipers to the tenth level on which hunting is suppressed but on which the hunting of the associated junction hunter switch JH_1 is initiated 35 to extend the call to the manual board in the main exchange. When the operator plugs in, the discriminating digit is absorbed by the restoration of the D. S. R. wipers to normal. The operator then takes the request of the calling subscriber and dials back over the junction in order 40 to set up a verification connection via the D. S. R. and final selector, and on receiving the busy signal cuts in on the connection to ask the subscriber to repeat his number. The operator then 45 clears down the D. S. R. and final selector and if connection is required with a subscriber on an exchange accessible from the tandem satellite she proceeds to reset the D. S. R. which hunts to select a junction leading in the desired direction. Subsequent digits are repeated by the 50 D. S. R. to set up the desired connection. When the two subscribers are connected together, the operator clears down her connections thereby releasing the junction to the main exchange.

If connection is required with a subscriber adjacent to the main exchange, the operator after clearing down the verification connection takes up the other plug of the cord circuit and inserts it in a jack extending to the desired exchange and the call is completed thereover as described.

In case a call is originated by a subscriber S_3 on the main exchange and is intended for another subscriber on the main exchange the connection is completed in a fully automatic manner over the line finder SF_2 on the lines described in connection with a local call within the tandem satellite exchange except that an ordinary first selector S is taken into use in place of the D. S. R., LD in the previous case. If however the subscriber requires a call external to his exchange he dials a distinctive digit for instance 0 and over the corresponding level of the first selector S obtains connection with the operator on the manual board. The operator re-

ceives his request and after verification of his number extends his connection over the other plug of the cord circuit in the desired direction. Should he require connection with a subscriber on the tandem satellite exchange TS, the operator will plug into one of the bothway junctions leading by way of the both-way junction equipment BE_3 to the incoming selector repeater SR at the tandem satellite exchange. Over this switch she is able to obtain access to the local 10 train of switches in order to set up the desired connection. Alternatively if connection is required with one of the R. C. X.'s via the tandem satellite exchange, the incoming selector repeater wipers will be raised to an upper level over which 15 access is had to outgoing junctions leading in the desired direction.

As regards the tandem R. C. X., TR, it should be mentioned that in addition to the arrangements for giving access to ordinary subscribers' lines 20 and outgoing junctions provision is also made for connection with 10-party line equipments constructed along the lines disclosed in the application of Owen Avis Pearce filed May 20, 1937, Serial No. 143,653. One set of bank contacts 25 only is allocated to each partly line of this type and connect with what is termed a 10-party line equipment PL adapted to control the setting of the selecting mechanism PI located adjacent to each of the subscribers' instruments. In these 30 circumstances the link circuit at the tandem R. C. X. is adapted to perform a repeating function after connection with the desired party line in order to pass on the additional train of impulses required for setting the mechanisms 35 PI.

In the case of revertive calls on a 10-party line circuit, the connection is verified and set up under the control of the operator at the manual board and when the two subscribers are connected together for conversation, the operator clears out of the connection leaving the party line tied to the link circuit for battery feed and supervision purposes.

Circuits typical of the two types of D. S. R. switches required in the tandem exchange are shown in Figs. 2-7 of the drawings. Figs. 2, 3 and 4 when arranged side by side show the circuit connections of a D. S. R. switch such as D_1 or D_2 in Fig. 1 suitable for terminating a bothway 50 junction from a tandem R. C. X. while Figs. 5, 6 and 7 when arranged side by side show a D. S. R. switch such as LD in Fig. 1 for use by subscribers local to the tandem satellite exchange. The mechanical construction of both the switches considered is that they are of the vertical and rotary type arranged to have so-called rectangular movement, that is to say, release takes place by further operation of the rotary magnet to advance the wipers clear of the bank after which they fall to the normal level and rotate back home beneath the bank. A switch of this type is disclosed in the application of Robert Norman Saxby, Patent No. 2,028,689, granted January 21, 1936. The junction hunter 55 switches employed are of the well-known unidirectional rotary type with reverse drive.

Considering now the operation of the incoming D. S. R. of Figs. 2-4, it will be understood that the leads -1 and $+1$ connect with an R. C. X., 70 bothway junction and leads -2 , $+2$ and P_2 extend from the D. S. R., bank multiple in the tandem satellite exchange for the purpose of outgoing calls to an R. C. X., the relays IC and OG and their associated contacts constituting a both- 75

way switching equipment such as BE1 in Fig. 1. Leads -3 and +3 connect with a bothway junction to the main exchange, and leads -4, +4 and P4 with an incoming selector repeater at the 5 tandem satellite exchange, the relays JA and JB constituting a bothway equipment such as BE3 in Fig. 1.

A call incoming from an R. C. X., subscriber is received as a pulse of earthed ringing current over 10 the incoming junction lead -1 and operates relay R over its lower winding which is connected to earth via condenser QE and shunted by rectifier MRA so as to be efficiently responsive to alternating current. Relay R thereupon at armature *r1* operates 15 relay B and locks over its upper winding while at armature *r2* it polarises the shunt field relay D1 which is inoperative at this stage. Relay B at armature *b2* operates relay IC which at armature *ic1* applies guard earth to the junction test lead 20 P2 in the D. S. R., switch multiple so as to mark the junction as busy. At armature *b1*, Fig. 4, a circuit is completed for relay RC which thereupon at armatures *rc2* and *rc3* connects relay K and the junction hunter switch driving magnet 25 JHM to the test wiper JH4. If the wipers of this switch connect in position 1 with an engaged main exchange junction, wiper JH4 will encounter earth either over armatures *ja4* and *jb1* if it is engaged by an incoming call received over 30 the junction or by way of the low resistance winding of a KA relay in another D. S. R., in the case of engagement on an outgoing call. Relay K will therefore be shunted and prevented from operating while an energising circuit will be completed for the magnet JHM by way of the magnet 35 interrupter contacts *jhm*. The magnet on energising disconnects its own circuit and since the switch is of the reverse drive type the magnet on releasing its armature advances the wipers to the 40 next position. This self-interrupted driving action continues until wiper JH4 encounters a free outlet which is marked by battery potential by way of the winding of relay JA whereupon relay K will operate in series with the magnet 45 JHM and relay JA in parallel. Due to the high resistance of relay K neither relay JA nor the magnet can operate in series therewith.

Relay K on operating, at armature *k4* disconnects relay RC which commences to release slowly 50 due to its slug, and at armature *k6* connects relay KA to the test wiper JH4. Relay KA being of low resistance provides a busying earth potential on the outlet seized, while this relay and relay JA operate in series. Relay JA at armatures *ja1* 55 and *ja2* connects the main exchange junction leads to the banks of the junction hunter instead of to the incoming selector repeater and at armature *ja4* operates relay JB in readiness for the subsequent release of the junction and busies 60 the junction in the selector repeater banks. During the release time of relay RC an earthed ringing generator is connected over common lead 11 and armatures *ka4* and *rc1* to the main exchange junction negative lead -3 so as to signal the operator at the manual board. On the release of 65 relay RC the ringing is disconnected from the junction and relays AO and OC are connected thereto over normal armatures of relays SY and RR and operated armatures of relays KA and K 70 in readiness for the reply of the operator.

In case all the main exchange junctions should prove busy, the junction hunter switch will rotate to the last position. This position is not wired to a junction and is not multiplied to other switches 75 so that the test wiper JH4 will encounter no po-

tential thereon and relay K will therefore operate in series with the magnet JHM. No circuit will be completed to operate relay KA however, and a busy tone transformer will therefore be connected over the common lead 12 and armatures *k3* 5 and *ka2* to the lower winding of relay AO whereupon busy tone will be extended by induction through the windings of relay AO on to the speech conductors. The tone then finds a circuit through condensers QA and QB back to the calling party. 10

Assuming that an idle line is found however when the operator plugs in and loops the calling junction relay AO operates, the differential relay OC in series therewith not being operated at this stage. At armature *ao1* a circuit is now completed 15 for relay RD by way of rectifier MRB and resistance YB. This relay at armature *rd2* prepares an impulsive circuit for relays CJ and C and the selector vertical magnet VM, relay C having already been operated over its left-hand 20 winding by way of armatures *b3* and *rr5* and resistance YC. At armature *rd4* a new holding circuit is completed for relay B over its lower winding, the initial operating circuit over its upper winding now being disconnected at the same 25 armature and also the upper winding of relay R. This relay remains operated however since at armature *rd5* its lower winding is bridged across the incoming speaking conductors in series with the left-hand winding of relay DI 30

It will be remembered that when an R. C. X. subscriber originates a call a calling signal is extended to the D. S. R. at the tandem satellite exchange and thence to the main exchange operator while at the same time an idle link circuit is caused to associate itself with the calling line. In case all links are engaged however, it is arranged to lock up the calling party's line relay until such time as a link becomes free when the operator will be signalled and the calling line 40 switched through. Should the calling party have hung up during this time, the operator is enabled to ring him and in order that she may be informed on plugging in the condition of the calling line a reverse battery supervision is provided 45 from the R. C. X. Thus if the calling party is on the line, relay DI in the D. S. R. will be operated and will operate relay SY over a circuit extending from earth over armature *c1*, contacts NR1 and armatures *oe3* and *di1*. This relay at 50 its armatures *sy1* and *sy2* reverses the battery potential by way of the windings of relays AO and OC to the main exchange junction so as to give the operator the necessary supervision. In case the operator on plugging in finds that the calling 55 party has hung up, she may ring him by operating a key at her position which extends an unbalance signal over the junction for example by the connection of earth potential to both the negative and positive conductors, and thereupon 60 operates the differential relay OC in series with relay AO. Relay OC at its armatures *oc1* and *oc2* repeats the unbalance signal back over the calling junction so as to bring about the ringing 65 of the calling subscriber at the R. C. X. When the calling party answers, relay DI is operated and in turn operates relay SY to signal the operator accordingly.

The operator now speaks to the calling R. C. X. subscriber to ascertain his requirements, and in 70 order to verify the correctness of the number which he gives as his own, she proceeds to dial back over the connection to set the connecting switch at the calling R. C. X. into engagement with the calling party's line. The first digit of the 75

calling party's number designates the calling R. C. X. junction in the tandem satellite exchange, and it is received on relay AO in the D. S. R. and serves to raise the wipers of this switch vertically to a distinctive level, as shown level 1, where a relay OE is operated by way of the vertical bank VB and wiper VW. This relay serves to by-pass the bridge circuit and to provide for the repeating backwardly over the calling R. C. X. junction of further dialled digits. This by-pass arrangement is employed in preference to a connection over the wipers of the D. S. R. so that in cases where there may be two or more R. C. X. junctions, the D. S. R. need not perform a hunting operation to connect with the particular junction over which it was taken into use. If it did not connect with the right junction it would be impossible subsequently to connect the calling subscriber locally with a subscriber on his own exchange and yet release the junctions used for the setting up of the connections.

Considering now the detailed circuit operation, on the reception of the first train of dial back impulses, relay AO responds and on the first release a circuit is completed from earth over armatures *dd3*, *rd1*, *ao1*, *dd2* and *rd2* to operate relay CJ and the vertical magnet VM and also to hold relay C. The switch wipers are now raised vertically one step whereupon the off-normal springs are mechanically operated and at contacts N2 complete a circuit for relay H over its lower winding from earth, contacts NR3, armature *c2*, off-normal contacts C2 and armatures *oe5* and *b4*. Relay H at armature *h3* short-circuits the left-hand winding of relay C so that during the remainder of the impulse train this relay will hold operated due to the combined effect of its slug and short-circuited winding, the slug on relay CJ enabling this relay to hold likewise. Relay CJ at armatures *cj1* and *cj2* disconnects any shunt paths such as the neon tube NT and relay TO from across the impulse circuit to relay AO so as to prevent interference with the operation of this relay during dialling. Relay RD is also intermittently short-circuited during the train but remains operated due to the slugging effect of the short-circuiting. The presence of the metal rectifier MRB in the energising circuit of relay RD prevents the slowing up of the magnet operation which would otherwise result by the direct connection of a comparatively low value non-inductive resistance in parallel with its winding. The resistance of relay RD is moreover such that neither the magnet VM nor relays CJ and C will hold operated in series therewith.

At the end of the train the switch wipers will have been raised vertically to the level corresponding to the digit dialled, say 7, and since this level characterises a call to be routed back to the originating exchange a strapping connection is made from the corresponding contact on the righthand side of the vertical bank VB to terminal OE, the connection being shown by lines intercepted by circles. Relay AO now remains steadily operated while relays CJ and C release after their slow release periods. On the release of relay C a circuit is completed to operate relay OE from earth over armature *b7*, off-normal contacts N5, armatures *rr1* and *c3*, vertical bank VB and wiper VW to battery via the winding of relay OE. This relay at armatures *oe1* and *oe2* by-passes the bridge circuit of the D. S. R. and provides an alternative loop across the calling junction comprising the windings of relays D and I in series. Relay OE also opens a point

in the circuit for relay C and the vertical magnet VM at armature *oe4*, and opens the circuit of relay H at armature *oe5* so that this relay now releases and permits the re-operation of relay C.

On the reception of further trains of impulses relay AO responds as before but this time only relay CJ operates and holds during each train. At armature *cj3* it short-circuits relays D and I so as to provide an impedance-free impulse repeating loop by way of armature *ao2* to the calling exchange for the duration of each impulse train.

After the dialling of the required digits the operator will be connected with the calling subscriber's line if the number given by him as his own is correct and the operator now receives a busy indication. As a further check she is enabled to cut-in on the engaged line by operating a so-called cut-in key at her position which unbalanced the circuit of relays AO and OC, and the latter now operates, relay AO remaining operated during this time over its upper winding. Relay OC thereupon at its armatures *oc1* and *oc2* repeats this signal over the junction so that the connecting side of the link in use at the R. C. X. will cut-in on to the engaged line and so enable the operator to ask the number of the subscriber connected with.

If the number given corresponds to the one which has already been given, the operator now clears down the verification circuit and this is done by extending a high voltage pulse over the junction which is received in the D. S. R. on relay TO connected across the speech conductors by way of a gas discharge tube NT. In response to the high voltage the tube strikes and lowers its resistance sufficiently to bring about the operation of relay TO which at armature *to1* operates relay RR by way of its lower winding. Relay RR upon operating, at armature *rr1* removes the short-circuit from its low resistance upper winding over which it now locks in series with relay OE, and at armatures *rr2* and *rr3* short-circuits condensers QC and QD and so completes a through metallic loop from the incoming main exchange junction to the R. C. X. junction so that the high voltage pulse may extend through to the R. C. X. where it brings about the operation of a further relay connected in circuit with a gas discharge tube to release the connecting portion of the link taken into use.

At armature *rr3* relays D and I are disconnected from the speaking conductors to prevent the operation of relay D by the high voltage while relay AO is also disconnected from the incoming junction and a local holding circuit is completed thereto by way of armatures *sy1*, *sy2* and *rr4* and resistance YA. At armature *rr5* the left-hand winding of relay C which has been energised due to the removal of the short-circuit therefrom when relay H restored is now disconnected so that this relay commences to release slowly due to its slug. At armature *rr6* a circuit is prepared for the D. S. R. rotary magnet RM in readiness for restoring the switch wipers to normal. On the release of relay C after its slow period, a self-interrupted driving circuit is completed for the rotary magnet RM from earth via armature *b7*, off-normal contacts N5, armatures *rr1* and *b6*, rotary magnet interrupter contacts *rm*, off-normal contacts N2, armatures *c2* and *rr6*, magnet RM to battery and the wipers are accordingly rotated to the 12th position where they restore vertically under gravity and then rotate under spring control under the banks

back to their full normal position where the magnet driving circuit is opened by the restoring of the off-normal contacts N2 and N5.

When the high voltage pulse is removed relay 5 TO releases, and the similar relays at the calling R. C. X. and at any intermediate tandem R. C. X. are also released. In case the associated switching apparatus, in this case the D. S. R., has not by then completely restored to normal relays RR 10 and OE will remain held until the release has been effected. On the restoration to normal of the D. S. R., relays RR and OE are released by the opening of the off-normal contacts N5 and these relays on releasing reconnect relay AO 15 across the incoming main exchange junction in readiness to respond to further dialled impulses if any, and disconnect the by-pass circuit between the two junctions.

If the call is intended for a subscriber on the 20 same exchange as the originating subscriber, the operator now dials the required number on to relay AO, the first digit of the number resetting the D. S. R. to the same level as before. Relay OE is therefore again operated and enables the 25 remaining digits of the number to be repeated by means of relay AO back over the calling junction to set the connecting portion of the R. C. X. link circuit into engagement with the required subscriber. It should be mentioned that at the 30 end of the first digit the reverse battery supervision of the calling party is disconnected in the link circuit from the junction in order to prepare for supervision of the called party. Hence when the latter answers after being rung the shunt 35 field relay D in the D. S. R. operates, its right-hand polarising winding being energised over the operated armature i_1 of relay I. Relay D at armature d_1 operates relay DD and this relay in turn at armature dd_1 brings up relay SY while 40 at armatures dd_2 and dd_3 it prepares a circuit for quickly releasing relay RD on the subsequent release of relay AO by removing any short-circuit or holding path. Relay SY at its armatures sy_1 and sy_2 reverses the battery potential supplied 45 by way of the windings of relays AO and OC in series to the main exchange junction so as to indicate to the operator that the called party has replied, while she will also hear the commencement of conversation.

The operator now withdraws her plug from the junction jack, whereupon relay AO releases and at armature ao_1 permits relay RD to release quickly. On the release of relay RD the holding circuit of relay B over its lower winding is disconnected at armature rd_4 and this relay commences to release slowly due to its slug, while at armature rd_5 relay K is released. Relay K at armature k_5 completes a homing circuit for the junction hunter switch over the following circuit:—earth, homing bank and wiper JH3, armatures k_5 and rc_3 , magnet interrupter contacts jhm , magnet JHM to battery and accordingly the wipers are rotated to the home position 1. Armature k_6 disconnects the holding circuit of relays 55 KA and JA which thereupon release and the latter at armature ja_4 disconnects the holding circuit of relay JB. During the release time of this relay the main exchange junction remains guarded by the application of earth over armatures ja_4 and jb_1 to the associated test contact in the junction hunter test bank JH4. On the release of relay B after its slow period, the circuit of relay OE is disconnected at armature b_1 and this relay releases. At armatures b_5 and b_6 a self-interrupted driving circuit is now completed

for the D. S. R. rotary magnet RM over the following circuit: earth which is supplied over common conductor 10 by way of suitable delayed alarm equipment, test link T (used for maintenance routine purposes), armatures c_4 and b_6 , 5 rotary magnet interrupter contacts rm , off-normal contacts N2, armatures c_2 and b_5 , magnet RM to battery. Accordingly the switch wipers are rotated to the 12th position whereupon they restore to the normal position in the manner 10 already mentioned. During their restoration relay IC in the incoming bothway junction equipment is held operated over armature c_1 and off-normal contacts N1 and subsequently releases 15 whereupon the guard earth is removed at armature ic_1 from the test lead P2 thereby marking the R. C. X. junction free for calls to the R. C. X.

If the call has been intended for a subscriber 20 on for instance an R. C. X. adjacent to the tandem satellite exchange, the operator on dialling back over the junction would have set the D. S. R. wipers vertically to a level such as 6 on which are situated junctions to the said R. C. X. In order to initiate rotary hunting over this level it is arranged that on the release of relay C at the end 25 of the vertical motion relay SA is operated over the following circuit: earth, armature b_7 , off-normal contacts N5, armatures rr_1 and c_3 , vertical bank VB and wiper VW, dotted strapping connection between the right-hand vertical bank 30 contact 6 and terminal LS, winding of relay SA to battery. It will be remembered that relay H is operated by way of its lower winding during the vertical motion of the switch and on the release of relay C this initial energising circuit is 35 disconnected but relay H now remains held over the same winding from earth by way of armatures h_1 and b_6 and the rotary magnet interrupter contacts rm . Relay SA at armature sa_6 completes an energising circuit for the rotary 40 magnet RM from earth over armatures h_1 and b_6 , contacts rm and N2, armatures c_2 and sa_6 , magnet RM to battery and the wipers of the D. S. R. are thereupon rotated into engagement with the first set of contacts in the level selected 45 while the magnet interrupter contacts rm are opened. The rotary off-normal springs are mechanically operated on the first rotary step and at contacts NR2 disconnect any further impulsing circuit for relay C and the vertical magnet VM. 50

A busy junction will be marked by earth potential on the associated P contact, while free junctions are detected by the absence of earth. Spare outlets on the level will be marked as busy by earthing the P contacts concerned.

If the first outlet encountered by the test wiper P is engaged as indicated by the presence of an earth potential, relay H will be held operated over its upper winding and the disconnection of its lower winding by the contacts rm is therefore without effect. The rotary magnet de-energises however, and on the closure of its interrupter contacts the magnet is re-energised to advance the wipers to the second set of contacts in the level selected. This stepping operation continues until a free outlet is reached, or alternatively the wipers are advanced to the 11th position where a busy indication is returned to the operator in a manner to be described.

Immediately the test wiper encounters a free 70 outlet relay H restores quickly and at armature h_1 disconnects the magnet driving circuit while at armature h_2 it applies an earth to the test wiper P to guard the outlet seized. At armature h_3 the short-circuit is removed from the left-hand 75

winding of relay C and this relay now re-operates and at armatures $c5$ and $c6$ extends the incoming junction by way of condensers QC and QD through to the wipers. A seizing loop comprising the windings of relays D and I in series is now extended to the connecting link at the distant R. C. X. so as to prepare it for trains of setting pulses.

In response to further dialling by the operator 10 of the remaining digits of the number, relay AO responds and at armature $ao2$ repeats the corresponding trains of impulses forward over the wipers of the D. S. R. to set the connecting link at the adjacent R. C. X. and route the call to its 15 required destination. Relay CJ is operated and held during each train of impulses in the manner already described so as to short-circuit relays D and I during the impulsive.

The calling party is then rung from the connecting link and when he answers the battery feed is reversed over the junction so that the shunt field relay D in the D. S. R. now operates, and operates relays DD and SY in turn. Relay SY upon operating signals the operator who withdraws her plug and releases relays AO and RD in turn. Relay RD at armature $rd5$ releases relay K which thereupon initiates the homing of the junction hunter switch and releases relays KA, JA and JB in the manner already described so as to free the main exchange junction. The incoming junction conductor -1 from the calling R. C. X. is thereupon connected over armatures $og1$ and $oe1$, condenser QB and armatures $cj1$, $k1$, $sa2$ and $c5$ through to the negative D. S. R. wiper while the conductor $+1$ is connected over armatures $og2$ and $oe2$, condenser QA, armatures $cj2$, $k2$, $rr3$ and $c6$ to the positive wiper. On the incoming side of condensers QA and QB relay R is bridged across the speech conductors by way of 40 armatures $rd6$ and $sa5$ and the left-hand winding of the shunt field relay DI and the operation of relay R completes a circuit to hold relay B over armatures $rd4$ and rl . On the other side of the condensers relays D and I are connected across the speech conductors and the two subscribers now converse with each other.

At the conclusion of conversation, when the calling party restores his receiver, relay R releases and releases relay B which initiates the release of the connection.

In case all junctions to the adjacent R. C. X. are engaged, the D. S. R. wipers are rotated to the 11th position where the cam springs are mechanically operated. Thereupon at contacts $S1$ the lower winding of relay AO is connected to the busy tone transformer so that busy tone is returned both to the operator and to the calling party. Contacts $S2$ disconnect the upper winding of relay H from the test wiper P so that on the opening of the interrupter contacts rm this relay releases as previously described and opens the magnet driving circuit in order to halt the movement of the wipers. On the subsequent withdrawal of the plug by the operator, relay AO restores to initiate release of the connection.

As regards relays OG and JB in the bothway switching equipments BE¹ and BE³ respectively, relay OG is operated on a call being extended from the main exchange through to the R. C. X. Relay JB is operated over the test lead P4 when the associated incoming selector at the tandem satellite exchange is taken into use from the main exchange and at armature jbl serves to guard the associated P contacts in the junction hunter multiple. Both junctions mentioned are operable

in a bothway manner depending on the direction of seizure.

Referring now to the local D. S. R. of Figs. 5, 6 and 7, it will be understood that the leads -1 , $+1$, P1 and M1 connect the switch back to back 5 with a line finder serving local subscribers at the tandem satellite exchange. Leads -2 and $+2$ connect with a bothway junction to the main exchange and leads -3 , $+3$ and P3 with an incoming selector at the tandem satellite exchange, 10 the relays JA and JB again constituting bothway junction equipment such as BE3 in Fig. 1.

Considering now the circuit operation, when a subscriber calls and the line finder locates his line, the loop extended forward over the incoming 15 conductors -1 and $+1$ operates relay A and this relay brings up relays B, BA and C in turn. Relay BA at armature $ba1$ connects up the dial tone transformer over common lead 13 to the middle winding of relay A whereupon dial tone 20 is returned to the calling party, while at armature $ba6$ a guard earth is applied to the incoming test lead P1.

In case the calling party desires to effect connection with another subscriber on the same exchange, he now dials the full number and in response to the first digit, impulses are extended over armature al to the D. S. R. vertical magnet VM so that the wipers are raised to the desired level. During the train relay B remains held due 30 to its slug, while relay CJ is also operated and holds during this time.

On local calls it may be necessary to absorb one or more of the digits dialled and in this instance it is assumed that the first digit of a local 35 number is absorbed. This is effected by providing a strapping from the level on the right-hand side of the vertical bank corresponding to the local digit to the terminal ABS. This results in the operation of relay M on the release of relay CJ 40 at the end of the first impulse train, the circuit being as follows: earth, armatures $ba4$ and $cj1$, vertical bank VB and wiper VW, strapping connection between the contact corresponding to the digit dialled on the right-hand side of the 45 vertical bank VB and terminal ABS, winding of relay M to battery. Relay M locks over its armature $m1$ and the off-normal contacts $N3$ to earth via armatures $oa1$, $rr1$ and $ba4$ and at armature $m8$ releases relay C. Relay C thereupon completes 50 a self-interrupted driving circuit for the rotary magnet RM from earth, armatures $oa3$, $m6$ and $ba2$, magnet interrupter contacts rm , off-normal contacts $N2$, armature $c3$ to battery via the magnet RM and accordingly the wipers are rotated 55 to the 12th position whence they restore to their normal position.

When the wipers reach the normal position, the off-normal springs are restored and by the opening of contacts $N3$ the upper winding of relay OA is inserted in series with the winding of relay M so that the latter now holds operated while relay OA operates. Relay OA at armature $oa1$ locks over its lower winding, at armature $oa2$ disconnects the dial tone circuit, at armature $oa3$ 65 re-operates relay C over its right-hand winding and at armature $oa4$ prepares a circuit for relay H over its lower winding in readiness for subsequent rotary hunting for a succeeding local switch on termination of the next dialled digit. At armature $oa8$ a circuit is completed to operate relay J by way of its lefthand winding in readiness for metering.

On the reception of the train of impulses corresponding to the next digit, relay A again re- 75

sponds and repeats them to the vertical magnet so as to raise the wipers to a level giving access to the local switches. On the first vertical step contacts N2 complete a circuit including contacts

- 5 NR2 and armatures c3 and oa4 to operate relay H and this relay at its armature h2 short-circuits the righthand winding of relay C so that during the impulse train this relay holds by virtue of its short-circuited winding, while relays CJ and B
- 10 also hold during this time due to their slugs.

At the end of the digit, relays CJ and C release after their slow periods in the usual manner and the latter at armature c3 initiates the rotary hunting operation, the earth being now supplied over operated armatures h1 and ba2. When a free outlet to a subsequent local switch is found, relay H releases quickly in the usual manner, disconnects the magnet driving circuit and at armature h2 removes the short-circuiting earth from

20 the right-hand winding of relay C. This relay now re-operates and at armatures c4 and c5 completes a seizing loop including armature a2 and the windings of relays D and I in series over the wipers to the subsequent switch taken into use.

25 Further digits dialled are repeated by armature a2 over the forward loop circuit extending via the wipers, the operated armature cj4 serving to short circuit the relays D and I during each train. The required local subscriber is therefore connected with over the final selector in well-known manner and he is then automatically rung. When he replies, battery is reversed back to relays D and I in the D. S. R. so that relay D now operates and at armature d1 brings up relay DD.

30 35 Relay DD at armature dd5 disconnects relay J and during the slow release time of this relay a metering pulse is extended back over either the incoming P1 or M1 leads as the case may be in order to operate the calling party's meter. In case fourth wire metering is employed the armatures dd6 and j4 serve to apply battery to the M1 lead while a strapping connection is made between terminals 14 and 15 and that between 15 and 16 is omitted. In case positive battery metering over the test wire P1 is employed the armatures j4 and dd6 are connected up by way of a strapping connection between terminals 16 and 15 to armature ba6, the connection between terminals 14 and 15 being omitted and the M1 lead not being provided. Thus it will be seen that local calls are completed and metered against the calling party in a fully automatic manner.

40 45 At the end of the conversation when the calling party replaces his receiver, relay A de-energises and brings about the release in turn of relays B, BA, C, M and OA. Relays D and DD are released either due to the called party hanging up or to the opening of the forward loop at armature a2. The D. S. R. is restored to normal in the manner 50 previously described when relay C releases. The incoming test conductor P1 is guarded in the usual manner over contacts N1 and armature c1 until the switch is fully restored.

55 In case all the local switches are engaged, the D. S. R. wipers are rotated to the 11th position where relay H is released at contacts S2 to disconnect the driving circuit while busy tone is returned to the calling party over common lead 12 and contacts S1.

60 65 70 If for any reason the incoming leads to the switch are looped and the call is not proceeded with, for example due to a faulty line or as a result of the subscriber accidentally leaving his receiver off the hook, it is arranged that the D. S. R. is automatically released after a suitable period as

measured by common timing equipment and the calling party's line equipment is then locked up to prevent further seizure of switches until the fault is cleared.

75 When the D. S. R. is taken into use, the left-hand winding of relay TP is connected over armatures dd1, m9, td6 and c2 to common lead S. The common leads S and Z extend to motor-driven cams arranged to supply earth pulses bearing a definite time relation. When the timing mechanism is in its normal position earth is applied to the S lead so that if the switch is taken into use some time during rotation of the cams earth will not be applied to the S lead until the mechanism returns to the normal position. When this occurs relay TP operates over its left-hand winding and thereupon locks over its right-hand winding. At armature tp3 earth is connected to the common start lead ST to cause the timing mechanism to perform another revolution while at armature tp2 relay B is connected to the common lead Z. After the lapse of the predetermined period, earth is applied to the Z lead and if the subscriber has failed to dial by this time, in which case relay TP will still be operated, the earth will be extended over armature tp2 to short-circuit relay B and cause its release. Relay B releases relays BA and C in turn and also relays M, OA and J if the absorbed digit has already been dialled and during the release of relay C the guard earth is removed from the incoming test lead P1 so as to bring about the immediate release of the line finder and the locking up of the calling party's line equipment. Relay A will have been released on release of the line finder and hence on the release of relay C the D. S. R. will now be available for further common use.

80 85 The forced release arrangement described will also come into operation if at the end of the conversation on a call not involving the manual board i. e. a call during which relay M is operated, the calling party should fail to hang up although the called party has done so. Under this condition relay TP will be connected up to the S lead over armatures dd1, m9, j5 and c2. The switch will be restored to normal in the usual way on the release of relay C.

90 95 In case the call is intended for a subscriber external to the tandem satellite exchange, the calling subscriber dials a distinctive digit which raises the D. S. R. wipers to a level on which relay TD is operated by way of the vertical bank and wiper and strapping connection between the righthand vertical bank contact corresponding to the digit dialled and terminal MB. Relay TD upon operating at armature td5 operates relay RC and at armature td7 disconnects the dial tone circuit. Relay RC at its armature rc1 and rc2 initiates the hunting of the junction hunter switch to select a junction to the main exchange and when this is found, relay K is operated in the manner previously described and at armature k3 applies guard earth to the junction hunter test wiper J4 whereupon relay JA in the bothway equipment is operated and subsequently relay JB. Relay K opens the circuit of relay RC and during the release time of this relay a short pulse of ringing is extended from common lead 11 and armatures k6 and rc3 to the negative junction lead -2 so as to bring the operator into the circuit. On the release of relay RC relays AO and OC are connected to the main exchange junction so that when the operator plugs in relay AO operates.

100 Relay AO operates relay RD by way of rectifier 75

MRB and resistance YD to battery and this relay thereupon at its armature *rd3* disconnects the righthand energising winding of relay C which now releases. A self-interrupted driving circuit 5 for the rotary magnet RM is now completed as follows:—earth, armatures *oc3*, *rd4* and *ba2*, rotary magnet interrupter contacts *rm*, off-normal contacts *N2*, armature *c3*, magnet RM to battery. The switch wipers are thereupon restored to normal 10 in the usual manner and when they reach this position, the off-normal contacts restore and at contacts *N2* disconnect the magnet driving circuit. At contacts *N3* the short-circuit path previously existing across the upper winding of 15 relay OA is removed and this relay now operates from earth, armatures *ba4* and *rr2*, upper winding of relay OA, armature *td1* to battery via a protective resistance. Relay RD also at armature *rd2* transfers the vertical magnet impulsing 20 circuit to the control of relay AO. Relay OA in addition to bringing about other circuit changes, at armature *oa6* operates relay SY which thereupon at armatures *sy1* and *sy2* reverses the battery extended on to the main exchange junction 25 by way of the windings of relays AO and OC so as to provide a supervision to the operator that the D. S. R. has restored to normal. Hence after speaking to the calling party and ascertaining his requirements she may at once set up a verification 30 connection.

For verification purposes the operator now dials the number of the calling party and the impulses operate relay AO which brings about the raising of the D. S. R. wipers to a distinctive 35 local level on which a strapping connection is made between the corresponding contact on the righthand side of the vertical bank and terminal LOC. Hence at the end of the first digit relay M is operated over armature *rd5*. Relay H is op- 40 erated over its lower winding in the usual manner on the first vertical step since relay OA is operated and consequently on the release of relay C at the end of the train a self-driving circuit will be completed for the rotary magnet. When a 45 free outlet to a succeeding local switch is found, relay H releases and re-operates relay C so as to extend a seizing loop comprising the windings of relays D and I in series and the operated armature *ao2* over the wipers of the D. S. R. to the 50 switch taken into use. Further digits dialled by the operator are repeated by this armature *ao2* so as to set up the local train of switches and thus obtain connection with the calling subscriber. If the operator encounters a busy indi- 55 cation, as should be the case if the correct number has been given, she may cut-in on the engaged line by unbalancing the junction line to bring up relay OC which at its armatures *oc1* and *oc2* relays the unbalance signal to the final se- 60 lector to cause it to cut-in.

Having identified the calling subscriber, the operator now extends a pulse of high voltage over the junction to release the verification connection and this is received on relay TO which is bridged 65 across the loop in series with the gas discharge tube NT and which upon operating energises relay RR. Relay RR breaks the loop forward over the D. S. R. wipers at its armature *rr5* so as to release the local train of switches and also at 70 armature *rr1* locks over its upper winding in series with relay M and opens the locking circuit of relay OA so that this relay is now dependent on the operated armature *ao2*. Hence at the completion of the high voltage pulse when relay 75 TO releases, the relay OA also restores and re-

leases relay C which completes the D. S. R. release circuit so that the wipers are again restored to normal. When this occurs the opening of the off-normal contacts *N3* allows relays RR and M to release. Since relay TD is still held operated 5 from earth over armatures *ba4* and *rd1*, relay OA will now operate again over its upper winding and re-operate relay C in readiness for a further vertical movement.

If the call is to be completed via an R. C. X. 10 accessible from the tandem satellite exchange, the operator now dials back over the junction so as to set the D. S. R. to a particular local routing level carrying junctions to the required adjacent R. C. X. The corresponding level of the vertical 15 bank is again connected to terminal LOC so that on the release of relay CJ at the end of the train of impulses, relay M is operated and locks over its armature *m1* in series with the upper windings 20 of relay OA. Relay H is also operated at the beginning of the vertical movement and on the release of relay C at the end of the digit the switch hunts for a free junction extending in the desired direction in the usual manner. Further 25 impulses are now repeated by armature *ao2* over the junction to set up the desired connection.

The wanted party is now rung and when he answers battery is reversed over the junction to operate relay D which in turn operates relay DD and this relay brings about the operation of relay SY so as to signal to the operator that the called party has replied. The operator now docketts the call against the calling party, since metering is not automatically effected under these conditions, and removes her plug from the junction jack. Relay AO now releases and re-releases relays RD, TD and K in turn so as to free the main exchange junction for further use, the two subscribers being linked together by way of the D. S. R. 40

If the call is intended for a subscriber on an exchange accessible from the main exchange, the operator after setting up and releasing the verification connection takes up the other plug of her cord circuit which she plugs into a jack connect- 45 ing to a junction leading in the required direction.

On all calls described it will be noted that the release of the D. S. R. is under control of the calling party, relay A in releasing initiating the 50 release of the D. S. R. at its armature *a1* by releasing relays B, BA and C in turn and opening the loop forward at armature *a2*. In the case of a main exchange call the armature *a2* also breaks the battery feed normally extended via 55 relay AO to the main exchange junction so as to give a clearing signal to the main exchange. The junction hunter in this case is also restored to the home position on release of relays TD and K in turn following that of relay BA. 60

In case on a call to the manual board all main exchange junctions are engaged, the junction hunter wipers are rotated to the last position where relay K is operated in the manner described in connection with the switch of Figs. 65 2-4 and operates relay J to return a busy indication to the calling party.

Contacts on the right-hand side of the vertical bank which correspond to spare code digits are cross-connected to terminal SC so that in the 70 event of such digits being dialled relay J will be operated to return a busy tone.

We claim:

1. In a telephone system, a main exchange, a tandem exchange, junction lines interconnecting 75

- said exchanges, a discriminating selector repeater unit in the tandem exchange including a hunting switch and a numerical switch, local switches in the tandem exchange, exchanges adjacent said 5 tandem exchange, means in said unit responsive to the receipt of a call for operating said hunting switch to select an idle junction line extending to the main exchange, and means in the main exchange for transmitting impulses back over the 10 selected junction line to operate said numerical switch to extend the connection to said local switches or said adjacent exchanges.
2. In a telephone system, a main exchange, a local exchange, junction lines interconnecting 15 said main and local exchanges, a discriminating selector repeater unit including an individual hunting switch and an individual numerical switch in the local exchange, local switches in the local exchange, an exchange adjacent said local exchange having access to said unit and accessible from the banks of said numerical switch, means in said unit responsive to the receipt of a call from one of said adjacent exchanges for operating said hunting switch to select an idle 20 one of said junction lines extending to the main exchange, means in the main exchange for transmitting impulses back over the selected junction line to said unit, means in said unit for repeating said impulses, and wipers in said numerical 25 switch operated in response to the first digit of said repeated impulses for extending the connection to one of said local switches to establish a path for transmission of the succeeding digits of said repeated impulses.
3. In a telephone system, a main exchange, a tandem exchange, junction lines interconnecting 30 said exchanges, a discriminating selector repeater unit in the tandem exchange including a hunting switch and a numerical switch, means including a two-conductor trunk line for seizing said unit 35 in response to the initiation of a call over said trunk line, means in said unit responsive to said seizure for operating said hunting switch to select an idle junction line extending to the main exchange, means in the main exchange for transmitting series of impulses back over the selected junction line to said unit, means in said unit responsive to the first of said series of transmitted impulses for operating said numerical switch 40 to extend the connection back to said two conductors of said trunk line, and means in said unit for repeating the remaining series of impulses back over said two conductors of said trunk line to complete the desired connection in 45 accordance with the repeated impulses.
4. In a telephone system, a main exchange having an operator's position, a local exchange, junction lines interconnecting said exchanges and terminating in said position, a discriminating selector repeater unit in the local exchange, local subscribers' lines terminating in the local exchange, local switches in the local exchange for extending connections to said local lines, exchanges adjacent said local exchange, a numerical switch included in said unit having access to 50 said local switches and to said adjacent exchanges, a hunting switch included in said unit having access to said junction lines, means whereby said numerical switch is operated by a calling one of said local lines to extend a connection from the calling line to said local switches in case the calling party desires a connection to a local called line, and means whereby said hunting switch is operated to select an idle one of said junction lines to said position and said numerical 55

switch is operated over the selected junction line by the operator at said position to extend a connection from the calling line to one of said adjacent exchanges in case the calling party desires a connection including said adjacent exchange. 5

5. In a telephone system, a first exchange, a second exchange having an operator's position, a third exchange, a discriminating selector repeater in the first exchange, a calling line in the first exchange, means including said selector repeater controlled by the calling line for setting said selector repeater to extend a connection from the calling line to said operator's position in response to the calling party dialling the initial digit for setting up a call to said third exchange, and means controlled by the operator for reoperating said selector repeater to extend said call to said third exchange. 10

6. In a telephone system, a first exchange, a tandem exchange, a main exchange having an operator's position, a discriminating selector repeater in the tandem exchange, a junction line extending from the first exchange to said selector repeater in the tandem exchange, means responsive to a call in the first exchange for seizing said selector repeater over said junction line, means responsive to said seizure for extending the call through the tandem exchange to said operator's position in the main exchange, means for transmitting series of digit pulses from said operator's position to said selector repeater, means in said selector repeater operated in response to the receipt of the first of said transmitted digits, and circuits completed by said last means for repeating the succeeding transmitted digits back over 30 said junction line to said first exchange. 35

7. In a telephone system as claimed in claim 1 including means for immediately releasing the numerical switch of said selector repeater unit after its operation in case the impulses transmitted over said junction line comprise a digit of a predetermined value. 40

8. In a telephone system as claimed in claim 5 including means in said selector repeater for transferring the control of said connection to said calling line in response to operator withdrawing after completion of the desired connection. 45

9. In a telephone system as claimed in claim 3 including circuits in said unit for repeating impulses back over said two-conductor trunk line, said circuits being prepared in response to said operation of said numerical switch by the first series of impulses transmitted from the main exchange. 50

10. In a telephone system as claimed in claim 4 including means whereby said hunting switch is operated to select an idle junction line to the operator's position only in case said numerical switch is operated in response to the receipt of a predetermined train of impulses from the calling line. 60

11. In a telephone system as claimed in claim 4 including means whereby said hunting switch is operated to select an idle junction line to the operator's position only in case said numerical switch is operated in response to the receipt of a predetermined train of impulses from the calling line, and means for restoring said numerical switch to its normal position in response to the operator replying. 65

12. In a telephone system as claimed in claim 4 including means for transmitting digits from the calling line to control said operation of said numerical switch and said hunting switch to es- 70 75

tablish said desired local connection or said connection to an adjacent exchange dependent upon the value of the first transmitted digit.

13. In a telephone system as claimed in claim 2 including means at the main exchange for transmitting a signal comprising a high voltage pulse over said selected junction line to said unit, and means in said unit responsive to receipt of said signal for restoring said numerical switch to normal.

14. In a telephone system as claimed in claim 3 including means at the main exchange for transmitting a signal comprising a high voltage pulse over said selected junction line to said unit, and means in said unit responsive to receipt of said signal for restoring said numerical switch to normal and for connecting said signal to said two conductors of said trunk line over which said unit was seized.

15. In a telephone system as claimed in claim 3 including a timing device effective after a predetermined time to release the connection in case no impulse transmission takes place and in case the calling party delays to hang up after the called party has done so.

16. In a telephone system as claimed in claim 6 wherein said selector repeater in response to said first digit is operated to a position characteristic of said first exchange before said circuits are effective to enable the operator to dial back over said junction line to said first exchange.

17. In a telephone system as claimed in claim 6 including means for giving the operator a signal to indicate whether the party originating the call is still on the line when said call is extended to said operator's position.

18. In a telephone system as claimed in claim 6 including means effective after the connection has been set up to the operator for reoperating said selector repeater to establish a verification connection to the party originating the call.

19. In a telephone system, a main exchange, a tandem exchange, junction lines interconnecting said exchanges, a discriminating selector repeater unit in the tandem exchange including a hunting switch and a numerical switch, local switches in the tandem exchange, exchanges adjacent said

tandem exchange, means including a two conductor trunk line for seizing said unit in response to a call from one of said adjacent exchanges, means in said unit responsive to said seizure for operating said hunting switch to select an idle junction line extending to the main exchange, means in the main exchange for transmitting series of impulses back over the selected junction line to said unit, means in said unit responsive to the first of said series of transmitted impulses for operating said numerical switch to extend the connection to said local switches or to said conductors of said trunk line dependent upon the number of impulses in said first series, and means in said unit for repeating the remaining series of impulses to said local switches or back over said two conductors of said trunk line dependent upon the extension completed in response to said first series of impulses.

20. In a telephone system, a main exchange 20 having an operator's position, a local exchange, junction lines interconnecting said exchanges and terminating in said position, a discriminating selector repeater unit including a hunting switch and a numerical switch in the local exchange, 25 local switches in the local exchange, exchanges adjacent said local exchange, local subscribers' lines terminating in the local exchange, means responsive to the initiation of a call by a local subscriber for seizing said unit, means controlled 30 by the calling subscriber for operating said numerical switch and said local switches to complete a connection to a local called subscriber's line; means controlled by the calling subscriber, in case an external connection to an adjacent 35 exchange is desired, for operating said numerical switch to a distinctive position; means for automatically operating said hunting switch to select an idle junction line to said operator's position in response to said operation of said numerical switch to said distinctive position, and means controlled by the operator for releasing and re-operating said numerical switch to extend the connection to the desired adjacent exchange.
